UNITED STATES PATENT OFFICE.

JESSE D. COTTRELL, OF MILFORD, MASSACHUSETTS, ASSIGNOR TO EBENEZER D. AND GEORGE DRAPER, OF SAME PLACE.

IMPROVEMENT IN LOOMS.

Specification forming part of Letters Patent No. 40,442, dated October 27, 1863.

To all whom it may concern:

Be it known that I, JESSE D. COTTRELL, a resident of Milford, in the county of Worcester and State of Massachusetts, have invented a new and useful Warp-Delivering Mechanism for a Loom for Weaving; and I do hereby declare the same to be fully described in the following specification, and represented in the accompanying drawings, of which—

Figure 1 is a top view, and Fig. 2 an end elevation, of a loom-frame, lay, warp-beam, and warp-guide as made or provided with my invention. Fig. 3 is a vertical section taken alongside of the crank-shaft of the lay, and so as to exhibit the warp-guide and warp-beam with my said warp-delivering mechanism applied to them.

In the said drawings, A denotes the frame of a loom, while B is the lay, and C the yarn-beam or warp-roller, and D the yarn or warp guide, or the support over and on which the warps rest in their passage from the warp-beam to the breast-beam E.

The warp roller or beam C is provided with a train of gears, *a b c*, for imparting rotary motion to it, they being arranged as shown in the drawings. A radial arm, F, turns freely on the shaft *d* of the gears *b c*, and carries near its outer extremity a pinion, G, and is provided with an abutment or stop, H, to arrest its upward movement, such abutment being made to project from the loom-frame.

At or near the middle of the radial arm F a lever-pawl, I, (formed in top view as shown in Fig. 4,) is jointed to a projection, *e*, rising upward from the said arm. This pawl at one end is so made as to engage with the pinion G in a manner to arrest rotary motion of the latter. At its other end the lever-pawl I has a projection, *f*, to extend over and upon the shorter arm of a right angular rocker-lever, K, whose fulcrum is the shaft *d*, and whose superior or longer arm is connected with the lay B by means of a connecting-rod, L, hinged or jointed to both lever and lay. Furthermore, a retaining-pawl, M, is applied to the periphery of the gear *e*, and is supported by and turns on a pin, *g*, extended from the side of the frame A. This pawl should not only be so constructed as to be capable of readily slipping out of action on the gear while the

latter may be in the act of being revolved in one direction by means of the radial arm and its pinion during an upward movement of them, but it should be made so as to hold the gear from revolving in an opposite direction.

The lever-pawl I is provided with an arm, N, which I term the "retainer," it being formed so as to extend across the retaining-pawl M and keep it in engagement with the wheel *e* during depression of the radial arm F. A depressor or rod, O, slides freely through the pin *g*. At its upper end the said rod O is jointed to the wrist of a crank or arm, P, extended from one of the journals *k k* of the yarn or warp guide D. At its foot the depressor O rests on the projection *f* of the lever-pawl I, the several parts above described being arranged with respect to one another as shown in the drawings.

The yarn or warp guide D is constructed in a peculiar manner. As generally made it consists of a "whip-roller," a horizontal shaft, and two arms projecting from the latter and supporting the journals of the whip-roller, the same being as shown in the United States Patent No. 36,029. In the use of this latter construction of the guide the warps rest both on the shaft and the whip-roller. The more the whip-roller may be depressed the more will the warps be wound on the shaft, and of course the greater will be the friction of the yarns or warps upon such shaft, over which they are usually strained very tightly.

My improved warp-guide D is constructed so that any downward movement of the guide will tend to diminish rather than to increase its extent of bearing-surface on the warps, and consequently either render the friction less or maintain it at about the same degree. My said improved guide D consists of a long plate, *p*, and the journals *k k*, extended from the opposite sides of the plate. The plate *p* is curved transversely, and is so arranged that its yarn-bearing surface shall extend upward from or quite near to the common axis, or the prolongation of the axes of the two journals, the same being as shown in Fig. 5. By this construction of the guide, whenever its plate *p* may be depressed by the strain of the warps, there will be little or no sliding motion of the plate at *r*, the prolongation of the axes of the

two journals, and the greater the depression of the plate the less will be the bearing of the warps on it.

The pressure to elevate the plate *p* is produced by means of a helical spring, *s*, which at its foot rests on a shoulder, *t*, and at its head or upper end bears against a lever, *u*, which has its fulcrum *v* projected from a post, *w*. An arm or lever, *x*, projects from the warp-guide *D*, and immediately over the lever *u* and underneath a projection, *y*, from the said post. A pitman, *z*, extends from one lever, *x*, to the other, *u*, each lever being provided with a rack or series of notches for reception and adjustment of the pitman. By means of the two levers *u* and *x* the pressure of the spring on the guide will be equalized during the movements of the guide, and such pressure may be either increased or diminished by moving the pitman either nearer to or farther from the spring.

When the lay moves back and the harness is sprung, the tension of the warp upon the warp-guide *D* will depress it, and thereby cause the depressor *O* to press down upon the three-armed lever-pawl *I* and trip it out of action with the pinion *G*. This three-armed lever having its fulcrum upon the radial arm *F*, which supports said pinion, the tendency of the pressure will be not only to raise the pawl out of the pinion, but at the same time press the retainer *N* against the pawl *M* and maintain it in the large gear *c*, and thus prevent such gear from being revolved by the tension of the yarn or warps on the beam when the lever pawl *I* may be disengaged from the pin-

ion *G*. During the disengagement of the lever-pawl *I* from the pinion the radial arm *F*, which sustains the pinion, will drop down by its own weight combined with the pressure upon it by the depressor *O*. It will drop one or more teeth or none at all, according to the strain upon the warp-guide. When the lay moves forward, it will cause the lever *K* upon the shaft of the principal gear, *c*, to press upward the lever-pawl *I* and the radial arm which sustains the pinion-gear, and as the latter will be held by the pawl from turning around it will rotate the gear *c*, whereby the warp-beam will be turned around so as to let off or deliver the yarn or warp.

I claim—

1. The combination for operating the train of gears of the warp beam, the same consisting of the radial arm *F* and its pinion *G*, the lever-pawl *I* and its retainer *N*, the retaining-pawl *M*, the depressor *O*, and the rocker-lever *K*, the whole being applied to the lay and the warp-guide substantially as and so as to operate as described.

2. The combination and arrangement of the two arms or levers *u* *x* and their pitman *z* with the spring *s* and the warp-guide *D*, also the combination therewith of the toothed racks or their equivalents to receive and hold the pitman and admit of its adjustment, for the purpose set forth.

JESSE D. COTTRELL.
